FLUID LOCK

John S. Pace, Jr., 7 Woodlawn Lane, Alexandria, Va.
Filed May 29, 1961, Ser. No. 113,562
6 Claims. (Cl. 24—221)

(Granted under Title 35, U.S. Code (1952), sec. 266)

The invention described herein may be manufactured and used by or for the Government for governmental purposes without the payment of any royalty thereon.

The present invention relates to fluid driven locks which combine both linear and rotary motion.

An object of this invention is to provide a lock capable of operation by remote control, and capable of exerting great force, both in a linear and a rotary direction, while closing and opening, and of holding against great force while in the locked position.

Another object of this invention is to provide a lock capable of linear and rotary motion, which is suitable for use in a series of said locks which are controlled simultaneously by a single set of controls and operating from a single fluid pressure source.

Other objects and advantages will be apparent to those skilled in the art upon reference to the following descriptions in the accompanying drawings in which:

FIG. 1 is a linear cross-section of a preferred embodiment;

FIG. 2 illustrates a combined shaft and locking lug of the fluid lock illustrated in FIG. 1;

FIG. 3 is a section on line *d*—*d* of FIG. 1;

FIG. 4 is a section on line *a*—*a* of FIG. 1;

FIG. 5 is a section on line *b*—*b* of FIG. 1;

FIG. 6 is a section on line *c*—*c* of FIG. 1;

FIG. 7 illustrates a method of controlling the linear and rotary motion of the lock individually; and

FIG. 8 illustrates a method of fluid pressure control of the lock by sequencing its linear and rotary motion.

Referring in detail to FIG. 1, a preferred embodiment of the fluid lock has, as its moving element, a combined splined and pistonized shaft 1, the shaft portion thereof operating within a cylinder tube 8 and a rotor tube 6. Rigidly secured to the end of the combination splined and pistonized shaft 1 is a piston 9, which, in the linear movement of the shaft 1, will move from a position close and nearly adjacent to cap 18 to a position close and nearly adjacent to cartridge 20, and return to its original position. The force causing this motion is created by the introduction of fluid through port 10 and the simultaneous evacuation of fluid through port 11, to cause the linear opening motion; and the introduction of fluid pressure into port 11 together with the simultaneous evacuation of fluid through port 10 to cause a closing linear motion of the lock. As seen in FIG. 1, fluid pressure introduced through either port 10 or port 11 will cause the fluid to enter the cylinder tube 8 and bring pressure to bear upon either side of piston 9. Piston 9 is provided with packing 17.

Rotary motion of the lock can take place simultaneously with the linear motion, or separably at any linear position of the lock which might be fixed by the stoppage of the flow of fluid into and out of ports 10 and 11. Rotary motion takes place upon the exerting of force upon the rotor blades 16 which is transmitted to the shaft 1 through splines 2. FIG. 3 illustrates a preferred embodiment of the rotor tube 6, showing the inter-relationship of the rotor blade assembly 21 and the splined portion of the shaft 2, as well as stops 23 which serve to limit rotary motion and to inclose the individual blades 16 within a chamber. The blades 16 and the stops 23 are provided with packing 24. Counterclockwise rotary motion of the shaft is accomplished by the introduction of fluid pressure into ports 14 and 13 with the simultaneous

2

evacuation of fluid through ports 12 and 15. Clockwise rotary motion is, of course, produced by the introduction of fluid pressure through ports 12 and 15, with the simultaneous evacuation of fluid through ports 13 and 14.

5 FIG. 4 shows another cross-section of the rotor tube with mounting head 5.

Snugly surrounding the shaft 1 between the cylinder tube 8 and the rotor tube 6 is a cartridge 20 (furnished with packing 19), threadably connected on its periphery 10 to sleeve 7, which effectively separates the piston and rotor portions of the lock and serves also to stop outward linear motion of the shaft.

The locking means, or connection means, of the preferred embodiment as shown by FIGS. 2, 5, and 6, comprise a disk-shaped portion 3 proximal to the splined portion of the shaft, a T-catch portion 4 at the distal portion of the shaft, and a cylindrical intervening section. The connecting means such as that shown in the preferred embodiment enable the T-shaped lug 4 to engage a slot 15 in a member to be locked by rotation of the lock. Then with the closing linear motion of the lock, as described above, the locked member would be drawn up securely against the member upon which the fluid lock is mounted.

FIG. 7 depicts schematically a means of individually 20 and separably controlling the linear and rotary motion of the lock. Pump 27 is the pressure source. Fluid is returned to reservoir 28. Control valves 25 and 26 each allow individual control of their respective linear and rotary functions. When valve 25 is in the parallel position, 25 the piston travels to the open position and when valve 25 is in the crossed position, the piston travels towards the closed position. When valve 26 is in its parallel position, rotation (see FIG. 3) is clockwise, and when valve 26 is crossed, rotation is counterclockwise.

35 FIG. 8 depicts a method of control whereby the linear and rotary motion of lock are sequenced, so that, in opening the lock with control valve 29 in the parallel position the linear motion takes place first, during and after which time, the fluid pressure and quantity is building up in a sequencing valve 30 in order that when linear motion is complete and rotary motion is free to take place there is sufficient quantity and pressure of the fluid within the line to cause the rotary motion to take place. With control valve 29 in the crossed position, pressure is immediately applied to the rotor tubes 6, at the same time allowing pressure to build up in sequencing valve 22 for linear motion after the rotary motion has proceeded to the point where the locking lug is uncoupled, at which time the linear closing can take place.

50 In the preferred embodiment, the lock is operated by oil under pressure; however, the lock may also be operated by any other liquid or by a gas. When appropriate, the protruding end of the shaft can be permanently attached to or made a part of the member which is to be

55 coupled and locked. Such would be the case when an assault bridge section is mounted upon a float or ferry. When not in use, the bridge section is maintained in a position superimposed over and parallel with the float or ferry. Prior to utilizing the bridge section as a portion of

60 an assault bridge, the shaft (of the vertically mounted fluid lock) upon which the bridge section rotates would be raised a few inches, thus disengaging the ends of the bridge section from the float or ferry, and then rotated 90°. The bridge section would then be lowered through the closing of the lock, thus re-engaging the bridge section with the ferry or float, the bridge section now being perpendicular to the ferry or float and in a usable position. The fluid lock is also extremely well adapted for use in securing folding bridge sections in their unfolded or working positions.

65 The linear movement of the lock can, of course, be varied in length of stroke and force of movement by a

proportional variation in the length of the shaft and cylinder and the diameter of the piston. A variation of pressure of the fluid will also create a corresponding increase or decrease in the force applied. The force of the torque actuator can, of course, be varied by increasing or decreasing the size of the rotor blades as well as by increasing or decreasing the pressure. By using only one rotor blade and one stop instead of two of each, as in the principle embodiment, the arc of rotation can be increased to nearly 360°.

The control systems shown in FIGS. 7 and 8 may be used to operate as many as eight fluid locks simultaneously simply by connecting them to the valves 25 and 26 in parallel (FIG. 7) or by connecting them to the sequencing valves 22 and 29 in parallel (FIG. 8).

Other possible uses of the fluid lock, not mentioned above, and not intended to be all inclusive, are for gun laying, material handling and for heavy gear shifting.

I claim:

1. A fluid operated lineal and rotary moving lock comprising a shaft, a torque actuator engaging said shaft, a cylinder, a piston operatively attached to said shaft and lineally and rotatably movable within said cylinder, mounting means for said torque actuator and cylinder, means for attaching said shaft to a structure for locking purposes, and fluid control means for the said torque actuator and said piston.

2. A fluid operated lineal and rotary moving lock as described in claim 1 where the means of attaching said shaft to a structure to be locked is a locking lug having a disk-shaped portion proximal to the said mounting means, a T-catch portion on its distal end, and a relatively narrow shaft-like intermediate portion.

3. A fluid operated lineal and rotary moving lock comprising a shaft having a splined portion, at least one rotor

blade lineally slidably and nonrotatably engaged upon the spline portion of the said shaft, a rotor tube encasing the outer edges of said rotor blade, fluid ports in said rotor tube so located as to provide fluid pressure application and fluid evacuation on either side of said rotor blade, a cylinder, a piston rigidly affixed to said shaft and lineally and rotatably movable within said cylinder, fluid ports at each end of the said cylinder, mounting means for said rotor tube and cylinder, means for attaching said shaft to a structure to be locked, and means of simultaneously applying pressure and evacuating fluid to and from said fluid ports on either side of said rotor blade and said piston.

4. A fluid operated lineal and rotary moving lock as described in claim 3 where the means of attaching said shaft to a structure to be locked is a locking lug having a disk-shaped portion proximal to said mounting means, a T-catch portion on its distal end, and a relatively narrow shaft-like intermediate portion.

5. A fluid operated lineal and rotary moving lock as described in claim 3 further including a sleeve threadably connected to said rotor tube on one end and said cylinder on the other end and a cartridge threadably connected with the sleeve on its periphery and snugly surrounding the unsplined portion of said shaft forming a barrier between said rotor tube and said cylinder and delimiting the lineal motion of said piston.

6. A fluid operated lineal and rotary moving lock as described in claim 3 where pressure applying means include sequencing valves disposed to sequence lineal and rotary motion of said lock.
